UNITED STATES PATENT OFFICE

155,551

DESIGN FOR AN AUTOMOBILE MIRROR

Robert K. Stortz, Delavan, Wis., assignor to Passing Eye, Inc., Kenosha, Wis., a corporation of Wisconsin

Application June 9, 1948, Serial No. 146,852

Term of patent 14 years

(Cl. D14—6)

To all whom it may concern:

Be it known that I, Robert K. Stortz, a citizen of the United States, residing at Delavan, in the county of Walworth and State of Wisconsin, have invented a new, original, and ornamental Design for an Automobile Mirror, of which the following is a specification, reference being had to the accompanying drawing, forming part thereof.

Fig. 1 is a side elevational view of an automobile mirror showing my new design;

Fig. 2 is a top plan view;

Fig. 3 is an end elevational view;

Fig. 4 is a sectional view taken on line 4—4 of Fig. 2;

Fig. 5 is a sectional view taken on line 5—5 of Fig. 2; and

Fig. 6 is a sectional view taken on line 6—6 of Fig. 2.

I claim:

The ornamental design for an automobile mirror, as shown.

ROBERT K. STORTZ.
